UNITED STATES PATENT OFFICE.

ANTHONY HARRIS, OF GREENOCK, SCOTLAND, AND FREDERIC ALFRED ANDERSON,
OF WESTMINSTER, ENGLAND.

SURFACE CONDENSER.

No. 901,809.

Specification of Letters Patent.

Patented Oct. 20, 1908.

Application filed April 25, 1905. Serial No. 257,374.

To all whom it may concern:

Be it known that we, ANTHONY HARRIS, a subject of the King of Great Britain and Ireland, residing in Greenock, Scotland, and 5 FREDERIC ALFRED ANDERSON, a subject of the King of Great Britain and Ireland, residing in the city of Westminster, England, have invented certain new and useful Improvements in Surface Condensers, of which the 10 following is a specification.

This invention relates to improvements in and relating to surface condensers and it has for its object to overcome the disadvantages arising from the corrosion of the copper or 15 Muntz metal surfaces or tubes due to the impurities contained in the circulating water.

It is known that metals such as those above specified may be to some extent protected against the corrosive action of the impurities 20 in the water by means of a mass of zinc suspended in such water and in metallic contact with the surfaces it is desired to protect. The disadvantages present in the above system have however been such as to prevent its 25 general employment and among these disadvantages may be instanced the necessity for preserving a bright or clean surface upon the zinc in order to insure its full and efficient action. This necessitates a more or 30 less frequent removal of the zinc for cleansing purposes. Further, the zinc is liable to rapidly disintegrate, particularly at the point of contact causing detachment and in any case the rapidity with which it wastes 35 away entails its renewal at inconveniently frequent intervals. Moreover, as zinc enters so largely into the composition of Muntz metal, the electro positive protection of some other metal than zinc itself seems preferable.

40 We have found that aluminium when employed in the manner specified not only prevents the corrosion of the tubes or surfaces but is not open to the objections previously enumerated, inasmuch as the surface thereof 45 remains clean and consequently the necessity for removing the mass to clean same is avoided. Further, the metal does not rapidly disintegrate. The preservation of the tubes or surfaces may be insured by employing a metal which is electro positive to the 50 surfaces to be protected, but which does not rapidly disintegrate.

In carrying the invention into effect we employ a mass of aluminium which is electro-positive to the surfaces to be protected. The 55

aluminium or other protective metal may be in the form of plates, bars or any other convenient form and may be placed in one or more of the water spaces, and suitably connected and in metallic contact with the surfaces to be protected. Thus for example, assuming the invention to be employed in conjunction with a condenser of ordinary form, a mass of aluminium may be secured in any convenient manner within one or both of the water spaces, the mass being in metallic contact with the tubes. The aluminium **may be** 60 secured to the tube plates in metallic contact therewith, means being provided if necessary to insure a proper contact between the said 65 tube plates and the tubes themselves.

While the above arrangement is given merely as a practical illustration of the application of the invention, it will be understood that it is not necessary that the protective metal be disposed within the condenser itself, as it may be disposed externally of the condenser or within a separate receptacle distinct from the condenser, and through which the circulating water may 70 pass to or from the said condenser, or in a suitable receptacle directly connected to the source from which the circulating water is derived. Under these latter circumstances the receptacle would preferably be of such 75 form and arrangement as to enable the water to be shut off therefrom, and also to enable ready access to the protective metal contained therein for the purposes of examination or renewal. It will of course be understood that the aluminium is in metallic contact with the surfaces to be protected—we 80 do not, however desire to limit ourselves to any specific arrangement or combination of parts for giving practical effect to our invention as it is considered that any application of aluminium which is electro-positive 85 to the condenser surfaces, fall within the ambit of the present invention.

An example of the application of the invention is shown in the accompanying drawings in which:

Figure 1 shows one end of a condenser, to which the invention has been applied, the end or cover being removed in order to show the arrangement of the blocks, the tubes being omitted. Fig. 2 is a similar view of the opposite end of the condenser. Fig. 3 is a longitudinal section. Fig. 4 is an enlarged view of a portion of the tube plate 105 110

with the protectors thereon. Fig. 5 is a sectional view to an enlarged scale showing the connection between the protector and the tube plate. Fig. 6 is a front view of one 5 of the protectors. Fig. 7 is an enlarged sectional view of an alternative form to that shown of 5 and 6; and Fig. 8 is a front view thereof.

In the appended drawings *a* indicates the 10 condenser shell, *b c d* and *e* the respective water spaces.

f f' indicate the tube plates, and *g* the protective masses of aluminium.

As will be seen on reference to Figs. 3, 4, 15 5 and 6, at the inlet end the tube plate is provided with studs *h* which are tapped into the plate *f* and upon which are mounted protective masses of metal *g* aforesaid. The 20 studs are each provided with sleeves or distance pieces *h'* and the mass is clamped thereon by means of a nut *h²*, vulcanite, or other suitable bushes *h³* being interposed between the end of a washer, disposed at the 25 end of the sleeve *h'* before referred to, and the nut *h²*, so that there is no contact between the supporting stud *h* and the mass *g*. Terminals *j* are secured to the mass *g* to 30 which are connected the ends of suitable cased conductors *j'*. The conductors are led through tubes *j''* to the opposite tube plate *f'* where they are stripped and placed in electrical contact with the tube plate by means of studs *j³* which are tapped into ferrules screwed into the tube plate in the ordinary manner, and beneath which may be provided a suitable gromet so that the perfect contact may be insured between the ferrule and the tube plate. It will thus be 35 seen that the mass *g* although supported on plate *f* is in metallic contact with the plate *f'*.

In order to afford local protection we may provide protective masses of metal *h* which may be secured directly to the tube plate. Masses such as those referred to are shown at Figs. 1, 2, 3, 4, 7 and 8. These masses 45 would be connected to the tube plate substantially in the manner as the masses *g* before referred to. In this case, however, the provision of insulating collars would not be necessary, the masses being secured directly 50 to studs such as those *h* before referred to, as shown in Fig. 7.

Obviously the number of the protective blocks and the position and method of connecting same with the surfaces to be protected may be varied in accordance with the 55 circumstances of each particular case.

Having now particularly described and ascertained the nature of our said invention, and in what manner the same is to be performed, we declare that what we claim is:—

In a surface condenser, the combination with the vessel containing the conduits for condensing, of a body of aluminium arranged to be immersed in the water in the 65 vessel, and in electrical connection with the portions of the conduit engaged by the water in the vessel.

In witness whereof we have set our hands in the presence of witnesses.

ANTHONY HARRIS.

FREDERIC ALFRED ANDERSON.
